Attorney

UNITED STATES PATENT OFFICE

ROBERT H. BLISS, OF EAST SYRACUSE, NEW YORK

WINDOW

Application filed May 6, 1929. Serial No. 360,790.

This invention relates to window constructions and particularly to metallic windows of the swinging sash type.

Many types of windows of the swinging sash type have heretofore been designed or suggested and many thousands have been manufactured and put into use. Recently metallic windows have been extensively manufactured, as it has been found that windows of this type present numerous advantages over windows of the prior type, constructed of wooden members. The present invention, while particularly directed to improvements in metallic window constructions, may nevertheless be embodied in wooden window constructions, as will be apparent to one skilled in the art.

The object of the invention is to provide a window comprising a frame and sash, in which the sash may be moved from closed to open position, or completely removed from the frame with great ease, and which is at the same time very simple in construction, may be easily fabricated, and is attractive in appearance. The invention may be embodied in windows which vary widely in physical appearance, not being limited in its usefulness to any particular type, and is very well adapted for embodiment in the well-known form of square or rectangular window commonly used for lighting and ventilating basements. In the accompanying drawings two such basement windows are illustrated, both of these windows being of the same general type but differing somewhat in details of construction, these windows being set forth merely by way of example, as the invention may be embodied in numerous additional specific forms of window constructions designed to suit various requirements of builders, designers and architects.

In the drawings:

Figure 1 is a front elevation of the improved window, showing the sash closed;

Figure 2 is a section on line 2—2 of Figure 1;

Figure 3 is a section on line 3—3 of Figure 1;

Figure 4 is a section on line 4—4 of Figure 1;

Figure 1 but showing the sash in different positions of adjustment;

Figure 5 is a plan view of the latching device, the latch being shown in dotted lines;

Figure 6 is a horizontal section through 55 portion of the swinging sash, showing the means for securing the window panes in position;

Figure 7 is a side view of the same;

Figure 8 is a section on line 8—8 of Figure 6;

Figure 9 is a rear elevation of one lower corner of the assembled frame and sash, showing a modified form of sash retaining arm; 65

Figure 10 is a section on line 10—10 of Fig. 9; and

Figure 11 is a sectional view similar to that of Fig. 10, but showing the sash in open, instead of closed position. 70

The improved window illustrated in Figures 1 to 8 inclusive comprises essentially a frame, generally indicated at 10 and a sash, generally indicated at 11. The frame, in the embodiment selected for purposes of disclosure, is rectangular, and is preferably formed of T bars rigidly secured together at the corners as by welding. The two vertical T bars 12 and 13 present their flanges to the front of the window, with webs rearwardly 80 directed, as does the upper horizontal member 14 of the frame. The lower horizontal member 15 also comprises a T bar but its flanged head is presented rearwardly and its web extends toward the front of the window. 85 As viewed in vertical section therefore, as for instance in Figures 3 and 4, the upper and lower frame T bars 14 and 15 are reversed.

The sash 11 comprises four similarly shaped angle members 16 rigidly secured 90 together to form a rectangular frame. Vertical T bars 17 connect the upper and lower angle member 16 of the sash at intermediate points and thus divide the area of the sash into three equal spaces. The glass plates 95 comprising the window panes are indicated at 18 and these plates are secured in position by securing devices hereinafter to be fully described. Between the margins of each plate or pane of glass and the metallic 100

member in front of the same are located strips of cork or the like, indicated at 20, which cushion the glass or provide a shock absorbing medium intermediate the glass and the supporting members of the sash, thus minimizing rattling and breakage. Preferably these cushioning layers are of cork and are glued to the metal frame members of the sash.

- 10 The vertical side members of the sash are spaced somewhat from the webs of the vertical side members 12 and 13 of the frame, as will be apparent upon an inspection of Figure 2 and in the spaces between the parallel side members of the frame and sash are positioned the swinging arms 21, 21, which are pivoted at their upper ends, as at 22, 22 to the vertical frame members, the pivots 22, 22 being in the same horizontal plane and aligned with each other so that arms 21, in effect, swing about a common horizontal axis. Each arm 21 is provided at its bottom with a projection 21' which extends rearwardly of the frame and each such rearward projection 21' has a laterally inturned extension 21² at its end which lies in the path of movement of the adjacent sash side member if the sash be rocked rearwardly upon its lower edge.
- 30 Each vertical side member of the sash is notched at 23, the notches being formed by striking up from the side members lateral projections 24. The notches are adapted to receive, respectively, the lateral projections 21² of the arms 21.

Pivoted secured at 25 to the top horizontal member of the sash is a latching lever 26 having a handle portion 27 and a catch-engaging portion 28. The catch-engaging portion is adapted to engage, when swung about its pivot 25, a catch 29 struck downwardly from the upper horizontal frame member 14. The latching device just described is described in detail in my Patent 1,706,100 granted March 29, 1929.

In Figure 3 the sash is shown in closed position and it will be apparent that the outer margin of its front face tightly engages a flat rearwardly facing cooperating surface of the frame. This makes a good weathering contact around the top and sides of the frame. At the bottom the horizontal portion of the bottom sash member simply rests upon the web of the bottom frame member 15. The sash is locked against inward movement by the latching device 27 at its top and the flange of the T bar 15 at the bottom.

To open the window it is first necessary to release the latching device by swinging it around the pivot 25 so that portion 28 disengages catch 29. The window can then be tilted to dotted line position A in Figure 4, at which time the notches 23 in the side members of the sash will engage the lateral projections 21² of arms 21. By pulling upon the

latch, or top bar of the sash, the sash may be further rotated about a horizontal axis which includes the upper edges of lateral projections 21², into the position in which it is shown in full lines in Figure 4. In this position the lower forward corner of the sash frictionally engages at its ends the rearwardly facing surfaces of the flanges of the side frame members 12 and 13. The window will be frictionally retained in this position. It may be easily lowered or completely removed. To remove the same it is only necessary to lift the upper end of the sash through a short distance or until projections 21² are disengaged from notches 23. After such disengagement the sash may be readily lifted from the frame and taken to any desired point.

In fabricating the window the distance between the upper edge of the projection 21² and the pivotal axis 22 is made less than the distance between notch 23 and the bottom of the swinging sash. That being so, it is possible only to swing the sash 16 through a limited angle around its pivotal axis located in the notches 23 in opening the same and hence there is no danger of the sash tilting backwards and being disengaged by members 21², and falling. In Figure 4 the sash is shown (position B) to be tilted very nearly as far as is possible for the construction shown.

The sash supporting arms may be so designed that they do not disengage the notches in the sash when the sash is closed. A construction of this kind is shown in Figures 9, 10 and 11. Here the lateral projections 40 of arms 40 lie in notches 41' of sash 41 at all times, except when the sash is completely removed from the frame. In this case the notches may be so positioned that the lower angle bar of the sash is slightly spaced from the lower frame member when the sash is in closed position. The notch 41' may be shaped in various ways, with the end in view of bringing about a movement in opening which is identical with that of the form first described.

It will be noted that the projections 40' of arms 40 lie intermediate the front and rear edges of the frame members, when the sash is in closed position (Fig. 10). These projections are therefore protected by the frame from damage during shipment. If desired the projections 21² of the form of the invention shown in Figures 1 to 8 inclusive may be caused to lie intermediate the front and rear edges of the frame members, for the same purpose.

It will be noted that, with both forms of the window disclosed, the vertical sash members have small portions thereof laterally deflected to overlie the adjacent swinging arm. Thus the projections 16' of the sash shown in Figures 1 to 8 inclusive, overlie the swinging arms 21, and the lateral projections 41' of the sash members 41 of the form of the

invention shown in Figures 9, 10 and 11 overlie the swinging arms 40. These projections have an important function i. e. they contact with, and return to their pendent vertical positions, the swinging arms, as the sash is moved to closed position, should these arms have a tendency to stick, or remain in the positions which they occupy when the sash is open.

10 The means for holding the panes of glass in position is shown in Figures 6, 7 and 8. Plugs or pins such as 42 are passed through the webs of the vertical T bars of the sash, at top and bottom, and lugs such as indicated at 43 are struck in from the webs of the vertical angle bars comprising the side members of the sash, these lugs being in the same horizontal planes as the cooperating pins 42. Flat resilient spring members 44 have their ends positioned inside of the pins and lugs and their central portions in contact with the glass. The action of springs 44 presses the pane of glass tightly against the cork facings 20 and the glasses are thus tightly held in position.

15 It will be understood that, while I prefer to form both the frame and sash of metallic shapes, preferably of angle bars and T bars, the invention is not limited to any particular 20 type or form of frame and sash members. Other structural metallic shapes may be employed if desired or wood strips utilized if preferred for any reason.

25 Having thus described the invention, what is claimed as new and desired to be secured by Letters Patent is:

1. A window construction comprising in combination, a frame having a vertically disposed seating surface for a movable sash, a sash the margin of which is adapted to bear against said seating surface when in closed position, and means on the frame for supporting the sash when it is moved to open position, said means wholly disengaging the 30 sash when the sash is in closed position.

2. A window construction comprising in combination, a frame having a vertically disposed seating surface for a movable sash, a sash the margin of which is adapted to bear against said seating surface when in closed position, and means on the frame for supporting the sash when it is moved toward open position so that the sash is movable about two horizontal pivotal axes in such 35 movement, said means disengaging the sash when the sash is in closed position.

3. In a window construction, the combination with a frame having vertically extending side members and a sash having side 40 members which are disposed parallel to and spaced slight distances away, respectively, from the side members of the frame, when the sash is in closed position, a supporting arm positioned in the space between each sash 45 side member and the associated frame side

member, said supporting arms being pivotally secured at their upper ends to the frame side members so as to swing about the same horizontal axis, and being provided at their lower ends with sash engaging and supporting means, which means is wholly disengaged 70 from the sash when the sash is in closed position, and which operatively engages the sash when it is tilted toward open position about its lower edge.

4. The combination set forth in claim 3 in which said arms are provided with lateral projections and the sash side members are notched to receive said projections respectively when the sash is tilted through a predetermined angle, about its lower edge.

5. In a window construction, a rectangular frame, a rectangular sash the bottom horizontal member of which rests upon the bottom horizontal member of the frame when the sash is in closed position, the sash having no permanent connection to the frame, and means whereby the sash may be supported from the frame when in open position, said means including elements pivotally 80 connected to the frame and having portions adapted to engage the sash when the sash is tilted from its closed position, said portions comprising pivotal points for the sash about which it may be turned from the vertical 85 toward a horizontal position as it is raised.

6. In a window construction, the combination with the relatively stationary frame and relatively movable sash, of arms pivoted to the frame and having portions adapted to enter notches formed in the sash when the sash is moved from its closed position, the said arms having a common horizontal pivotal axis and the distance between said notch engaging portions and the said pivotal axis, being less than the distance from the said notches to the bottom of the sash, for the purpose set forth.

7. In a window construction, in combination, a frame having vertical side members with rearwardly directed faces, a sash adapted for bodily movement vertically and pivotal movement about a horizontal axis in moving from closed to open position, and means pivoted to the frame for supporting the sash in an inclined position, with the front lower corner thereof frictionally engaging the rear faces of the frame side members.

8. In a window construction, a frame, a sash, and means connecting the frame and sash and causing the outer lower corner of the sash to frictionally bind against the frame at a point midway of the height of the frame, thereby holding the sash in open position.

9. In a window construction, in combination, a frame, a sash, and means for supporting the sash from the frame for tilting movement about a horizontal axis, said means wholly supporting the weight of the sash when the sash is in closed position.

10. In a window construction, in combination, a frame, a sash, and means for supporting the sash from the frame in both open and closed positions, said means supporting the sash for tilting movement about a horizontal axis, and supporting the sash with its lower horizontal member out of contact with the adjacent horizontal member of the frame when the sash is in closed position.
11. In a window construction, in combination, a frame, a sash, arms pivoted to the frame and which contact with the sash only when the sash is moved toward open position, and means on the sash to contact with said pivoted arms when the sash is moved toward closed position, for the purpose set forth.
12. In a window construction, in combination, a frame, arms pivoted at their upper ends to said frame, and having sash engaging portions adjacent their lower ends, the sash being adapted to be rocked about a horizontal axis defined by said sash engaging portions, and said arms being adapted to swing from normal vertical positions outwardly to inclined position when the sash is moved to open position, and means on the sash to engage said arms as the sash is moved to closed position and to swing said arms to normal position.
13. The combination set forth in claim 12 in which said last mentioned means comprises two laterally projecting portions of the side members of the sash, each of which overlies one of the associated pivoted arms.
14. A window construction comprising, in combination, a frame, a sash, and means on the frame adapted to cooperate with the frame in supporting the sash in open position with the lower horizontal member of the sash out of contact with the frame, which means disengages the sash when the sash is in closed position.
15. In a window construction, the combination with a relatively stationary frame and relatively movable sash, of arms pivoted to the frame and having portions adapted to enter notches formed in the sash when the sash is moved from its closed position, and to disengage said notches when the sash is returned to closed position, for the purpose set forth.

In testimony whereof I hereunto affix my signature.

ROBERT H. BLISS.
